(57) **CLAIM**

The ornamental design for a center console for automobile, as shown and described.

DESCRIPTION

1. Center console for automobile

1.1 : Perspective

1.2 : Front

1.3 : Back

1.4 : Left

1.5 : Top

1.6 : Bottom

1.7 : Reference photo

The broken lines depict portions of the center console for automobile that form no part of the claimed design. The dash-dot broken lines define the boundary of the claimed design and form no part thereof. Fig. 1.7 shows the claimed design in use.
